RECORDING AND REPRODUCTION OF
IMPULSES

Edward W. Kellogg, Moorestown, N. J., assignor
to Radio Corporation of America, a corpora-
tion of Delaware

Application March 9, 1933, Serial No. 660,159

7 Claims. (CL. 271—2.3)

This invention relates to the recording and reproduction of impulses such as those of audio-frequency, and has for its principal object the provision of an improved apparatus and method 5 of operation whereby the film or other record surface is given a smooth and uniform movement at the translation point where the impulses are recorded or reproduced.

In the recording or reproduction of sound, 10 when the record consists in a long flexible strip of material, such as a motion picture film for example, one method of insuring substantially constant velocity is to employ a cylinder which is caused to rotate at uniform speed and to cause 15 the record to be held sufficiently firmly against the cylinder so that it will not slip. Adequate pressure between the cylinder or drum and the record is sometimes secured by tension on the record but a more positive means of insuring 20 sufficient friction between the two is to employ one or more auxiliary rollers which press the record against the uniformly rotating drum. Such pressure rollers may be provided with yielding tires, of rubber for example.

If the record is subjected to a moderate degree of tension, there is usually little difficulty in causing it to remain snugly against the drum throughout the angle of wrap. It is very desirable, however, in certain constructions to 25 minimize the tension on the record and under these conditions, although a pressure roller such as has been described may prevent tangential slipping of the record with respect to the drum, the record may not remain firmly in contact with 30 the drum at all times at points within the arc of wrap which are not directly under the pressure rollers.

In some devices the record is pulled past the 35 point where recording or reproduction takes place and is guided and supported at the said point, for example, a stationary gate. It may be sufficient in such devices to insure that the record move uniformly at the one point where it is pinched between the drum and the pressure 40 roller. A common construction, however, is to effect the recording or reproduction at a point where the film is actually supported by the uniformly rotating drum. Under these conditions it is especially important that the record remain 45 definitely in contact with the drum at the recording or reproduction point. If the record is made photographically and reproduced optically, there is nothing in contact with the film at the recording or reproduction point to hold the film 50 against the drum and any failure of the record 55

to stay against the drum will mean that the optical system will be out of focus.

In order that vibrations of the record, due, for example, to the action of sprocket teeth which engage the record, may not cause vibrations of the record where it should be in firm contact with the drum, it may be desirable to employ two pressure rollers. This successfully isolates the portion of the film between the two pressure rollers. It sometimes happens, however, that a slight loop of excess length of film accumulates between the two pressure rollers, especially as has been stated if the film is not under appreciable tension. The purpose of my invention is to prevent the formation of such a 15 loop between the pressure rollers.

If the pressure roller, where the record is fed on to the drum, exerts a slight retarding force on the record due, for example, to friction in the pressure roller bearings, this has an effect similar 20 to tension on the film and helps to keep it tight around the drum. There is objection, however, to the application of any more retarding force than necessary, because the application of any frictional forces increases the difficulty of insuring uniform rotation of the drum. My invention provides means whereby a sufficient 25 retarding force may be applied against the record but the mechanical work taken up by the pressure roller at this point is in a large measure returned to the drum through a second connection. Thus the retardation of the drum is considerably 30 less than would be the case if the same amount of retarding force were applied at the record and the force were absorbed entirely in ordinary 35 bearing friction or by means of a brake.

In the case of the pressure roller where the record leaves the drum, which I shall hereinafter call the "second" pressure roller, it is desirable 40 that the roller exert a forward force on the record. This may be accomplished by means of an auxiliary driving system such as shown in my figures. Instead of the roller rotating on a stationary shaft, it is mounted on a sleeve which is driven at higher speed than that at which the roller 45 itself runs. This sleeve may be driven in any suitable manner but the purpose may be most simply accomplished by means of friction coupling or gearing to the drum shaft. In this construction the friction between the roller and the 50 sleeve provides the desired forward torque but it is obvious that said torque might be supplied through other forms of friction coupling between the roller and a member rotating at higher speed. If the power for driving the second pressure roller 55

is obtained from the rotation of the drum itself, a large part of this power is returned to the drum through the contact between the pressure roller tire and the record.

- 5 I regard the supplying of a forward force by the second pressure roller as of more importance than the provision of additional retarding force by the first pressure roller for the reason that the first pressure roller, even though mounted 10 in the usual way, will always apply a slight retarding force to the record. It is evident that the combined effect of the backward tangential force at the point of contact at the first pressure roller and the forward force at the point of contact with the second pressure roller is to subject the film between the two rollers to a slight tension, thereby insuring that the record will stay snugly against the drum throughout the intervening arc.
- 15 20 The invention will be better understood from the following description when considered in connection with the accompanying drawing and its scope will be pointed out in the appended claims.

- 25 Referring to the drawing,

Figs. 1 and 2 illustrate end and sectional views of a film gate wherein both the pressure rollers are driven.

- 30 35 Figs. 3 and 4 illustrate a modification wherein only the roller at the point where the film leaves the drum is driven, and

Fig. 5 illustrates an embodiment wherein both the rollers are driven through an idler gear mounted on the drum shaft.

- 40 45 The form of apparatus illustrated by Figs. 1 and 2 includes a drum 10 mounted at the end of a rotatable shaft 11. As shown more clearly in Fig. 1, a film or other record strip 12 passes around the drum under the control of a pair of pressure rollers 13 and 14 supported respectively by means of arms 15 and 16 or by other suitable means. Each of these rollers is provided with a frictional bearing surface 17 in order to permit their peripheries to move at the same speed 50 as the film irrespective of the fact that they tend to be driven at different speeds. In the apparatus of Figs. 1 and 2, the roller 13 is driven through a frictional disk 18 and a frictional surface 19 formed on the end of the drum 10 and the roller 14 is driven through a friction disk 20 and a frictional surface 21 formed on the end of the drum 10.

- 55 60 Under these conditions, movement is imparted to the film 12 by rotation of the drum 10, the rollers 13 and 14 tend to be driven respectively a little slower and a little faster than the periphery of the drum, and the film is at all times subjected to a tension which maintains it in close contact with the drum surface, thus insuring that it will remain in focus at the recording or reproducing point 22.

- 65 70 It will be apparent that this type of gate may form a part of a photographic recorder or reproducer or a part of a mechanical or electromechanical recorder or reproducer. In the arrangement of Fig. 1 it is shown as applied to a photographic recorder wherein suitably modulated light is applied to the film 12 at the translation point 22 through an optical system 23. In the case of a photographic reproducer, a constant beam of light is of course passed through the film to a light sensitive cell which may be supported within the drum by means of a stationary arm or the like.

In the case of mechanical or electromechanical

recording and reproducing employing a grooved record in the form of a tape or film, the optical system is replaced by a suitable cutter or pick-up device, and this invention serves the purpose of applying tension to the film at the point of translation.

5 It is sometimes sufficient that only one of the pressure rollers be driven. In the modification of Figs. 3 and 4, the roller 14 is driven through the friction pulleys 20 and 21 in the manner previously described and the roller 13 operates as an idler with some friction at its bearing.

10 15 As indicated by Fig. 5, the rotation of the rollers 13 and 14 may be controlled by means of an idler gear 24 interposed between gears 25 and 26 mounted respectively on the shafts of the rollers 13 and 14. With this construction, the forward pull of the roller 14 is balanced against the backward pull of the roller 13 and film is stretched snugly around the drum 10 as previously explained. The power required to supply the forward torque to the second pressure roller 14, is in the case of Fig. 5 derived from the first pressure roller 13, instead of directly from the drum as in Figs. 1 to 4. With the construction 20 shown in Fig. 5, it is unnecessary to provide sliding surfaces 17 in both rollers 13 and 14, and if only one such surface is provided, I prefer that it should be in the second pressure roller 14, the roller 13 and gear 25 being operatively integral. 25

30 35 In case it is found that the bearing surface 17 does not provide sufficient friction to impart as much forward torque to the roller 14 as is desired, adjustable brake means may be provided acting between roller 14 and gear 26, to increase the friction coupling between the two, but I have not found this measure necessary, sufficient friction being afforded by moderately small bearing clearance and the employment of a stiff lubricant.

40 I claim:

1. A record moving apparatus including a member provided with a record support surface, a roller for maintaining said record in contact with said surface, means tending to impart to the peripheral surface of said roller a speed which differs from that of said support surface, and means for causing said surfaces to be moved at substantially the same speed. 45

2. A record moving apparatus including a member provided with a record support surface, a roller for maintaining said record in contact with said surface, means tending to impart to the peripheral surface of said roller a speed which differs from that of said support surface, and means including a frictional bearing for permitting said surfaces to be moved at substantially the same speed. 50

3. A record moving apparatus including a rotatable drum, a roller for maintaining said record in engagement with said drum, means tending to impart to said roller a peripheral speed in excess of that of said record, and a frictional bearing for said roller whereby slippage between said record and said roller is obviated. 55

4. A record moving apparatus including a rotatable drum, a roller for maintaining said record in engagement with said drum, means tending to impart to said roller a peripheral speed somewhat lower than that of said record, and a frictional bearing for said roller whereby slippage between said drum and said record is obviated. 60

5. A record moving apparatus including a rotatable drum, a pair of rollers for maintaining said record in engagement with said drum, means

tending to impart to said rollers peripheral speeds which are respectively somewhat lower and somewhat higher than that of said drum, and frictional bearing means for permitting the peripheries of said drum and said rollers to be moved at substantially the same speed.

6. A record moving apparatus including a rotatable drum, a pair of rollers for maintaining said record in engagement with said drum, means including an idler gear tending to impart to said rollers peripheral speeds which are respectively somewhat lower and somewhat higher than that of said record, and frictional bearings for pre-

venting slippage between the surfaces of said drum and said rollers.

7. A record moving apparatus including a rotatable drum provided with a frictional surface, a roller for maintaining said record in engagement with said drum, means including said frictional surface tending to impart to said roller a peripheral speed different from that of said drum, and a frictional bearing for said roller whereby said roller is permitted to rotate with a peripheral speed substantially the same as that of said drum.

EDWARD W. KELLOGG.
